(57) **CLAIM**

The ornamental design for a linear light fixture, as shown and described.

DESCRIPTION

FIG. 1 is an isometric top front view of a linear light fixture showing our new design;

FIG. 2 is an isometric bottom rear view thereof;

FIG. 3 is a front view thereof;

FIG. 4 is a rear thereof;

FIG. 5 is a left view thereof;

FIG. 6 is a right view thereof;

FIG. 7 is a top view thereof;

FIG. 8 is a bottom view thereof;

FIG. 9 is a cross-sectional view thereof taken in the direction of line 9-9 of FIG. 7; and,

FIG. 10 is an exploded view thereof.

The broken line disclosure of the block-out structure forms no part of the claimed design.
